1

The invention relates to a counting or number registering mechanism, and in particular to a counting mechanism or a similar device, comprising normally juxtaposed figure wheels (*n*-partite for a numerical system based on powers of *n*), each intended for one of the positions to be occupied by a digit, and generally coupled by means for carrying the multiples of *n*.

More in particular, counting mechanisms for the decimal system will be considered, although the invention may also be used for other numerical systems after having been adapted thereto.

In arithmetics, it is known to check the correctness of arithmetical operations, *inter alia*, by casting out the nines, or by casting out the elevens. In casting out the nines, the so-called 9-function is determined for each of the numbers to be subjected to the operation; this function is equal to the sum of the digits, diminished by a multiple of 9 so as to leave a positive number less than 9.

In arithmetical operations (additions and subtractions, multiplications, divisions), the result of the operation has the same 9-function as the result obtained by applying the same operation to the 9-functions of the numbers involved in the operation. If a difference occurs between the 9-functions of both the results, a check must be made, as an error has crept into the calculations.

In casting out the elevens, a similar procedure is followed; however, the 11-function is equal to the sum of the digits appearing in the odd positions, diminished by the sum of the digits appearing in the even positions and further decreased or increased, if necessary, by a multiple of 11 so as to leave a positive number less than 11.

The above-mentioned checking methods are based on a more general rule, to the effect that, if numbers are subjected to an arithmetical operation and if the remainders obtained on division of these numbers by a certain key number S (*i. e.* the S-functions) are subjected to the same operation, the S-function of the result will correspond with the S-function of the result of the operation applied to the S-functions of the numbers. In this connection, the S-function of a number is understood to be equal to the difference between the number and the next smaller multiple of the selected key number S.

2

It is to be pointed out that casting out the nines brings to light 8 of any 9 arbitrary errors; not however the transpositions of directly adjacent figures which are frequently occurring in practice, nor any other errors resulting in a difference divisible by 9. Casting out the elevens reveals 10 of any 11 arbitrary errors; not however equal errors in directly adjacent figures or transpositions between units and hundreds, tens and thousands, etc., nor any other errors resulting in a difference divisible by 11. A greater certainty may be obtained by casting out the nines and the elevens in combination, or by making use of one or more other key numbers affording a greater probability of finding an error. For instance, the numbers 7, 13, 17, 19, 23, 29, etc. may be considered as key numbers.

The idea is obvious to introduce the procedure of casting out the S's in automatic calculating methods. In particular, it would be of importance to check the numbers inserted in an automatic calculating device in this manner, *i. e.* to check whether a number selected, for instance, by means of a plurality of keys, is right. For this purpose, the S-function of each number to be inserted in the machine could be separately determined, and the counting mechanism could be provided with a special checking wheel (S-partite for the S-functions). Upon striking a number, the corresponding S-function is struck on the checking wheel or wheels. As a consequence, the said S-functions are treated in the same manner as the numbers inserted in the machine. As soon as a result is obtained, it is possible to check whether the S-function of this result corresponds with the S-function displayed by the checking wheel at the same time. If there is a disagreement, an error has been made, and it is highly probable that this is an error made in striking the numbers. In any case, a continuous supervision would be obtained in this manner.

The invention has for its object to provide a solution of this problem which makes it possible to obtain the above-mentioned check without decreasing the speed of operation of the machine, notwithstanding the high speed of operation of modern counting and number registering mechanisms. According to the invention, the normal figure wheels are coupled for this purpose with a calculating device registering their positions,

computing therefrom the S-function of the number displayed by the normal figure wheels, and registering this function. Thus, the desired S-function is automatically computed for each number displayed by the mechanism at any time, so that this S-function may be compared with the S-function displayed by the checking wheel in question.

Strictly speaking, the separate checking wheel could be replaced by another device, on which or by means of which the S-function of the result of the operation applied to the S-functions of the various numbers is registered. However, in order to obtain a continuous supervision, it is essential that the S-function of the result appearing in the normal counting mechanism is automatically computed.

As a further development, the invention provides a comparing device automatically signalizing a disagreement between the position of the checking wheel as mentioned hereinbefore, and the result obtained by the said calculating device. At the same time, the comparing device may cause the mechanism to be locked, or its driving to be interrupted.

Preferably, the said calculating device will be an electric one, but mechanical calculating devices are also conceivable and practicable for this purpose.

An embodiment of the invention will be explained with reference to the accompanying drawings; in this embodiment, the nines and elevens are cast out in a decimal system.

Fig. 1 is a somewhat schematic plan view of a simple calculating machine. Figs. 2-10 are schematic cross sections of the counting mechanism of the machine shown in Fig. 1, which is provided with electric auxiliaries embodying the present invention.

Fig. 2 shows a plate carrying a plurality of contact brushes or feelers, arranged at the left of the counting mechanism, as viewed from the left.

Fig. 3 comprises, at the left, a front view of the left-hand side of the first figure wheel from the left, and at the right, a projection of the right-hand side of the same figure wheel. Both sides of the figure wheel are provided with contacts and with conductors interconnecting these contacts: the left-hand side cooperates with the brushes shown in Fig. 2, and the right-hand side with the brushes shown in Fig. 4.

Fig. 4 shows a feeler plate arranged between two successive figure wheels; a front view of the left-hand side is shown at the bottom, and a projection of the right-hand side at the top.

Fig. 5 comprises a front view of the left-hand side and a projection of the right-hand side of a normal figure wheel.

Fig. 6 shows a feeler plate arranged at the right of the counting mechanism; the right-hand side of this feeler plate, shown at the top in the figure, carries a plurality of brushes cooperating with a checking wheel for the 9-function, which is represented in Fig. 7.

Fig. 7 comprises a front view of the left-hand side and a projection of the right-hand side of the said checking wheel for the 9-function.

Fig. 8 comprises a front view of the left-hand side and a projection of the right-hand side of a feeler plate arranged at the right of the wheel shown in Fig. 7.

Fig. 9 comprises a front view of the left-hand side and a projection of the right-hand side of a

checking wheel for the 11-function, arranged at the right of the feeler plate shown in Fig. 8.

Fig. 10 is a front view of the left-hand side of a feeler plate arranged at the right of the checking wheel shown in Fig. 9.

The counting mechanism shown in Fig. 1 is enclosed by a casing 12, provided with a slot 13, through which one figure of each of the figure wheels 14¹-14⁷ is visible. The counting mechanism is shown in its zero position, wherein all figure wheels display a zero before the slot 13. A key board, comprising 7×10 keys, indicated at 15, serves for selecting numbers to be supplied to the counting mechanism.

A window 16, placed in alignment with the slot 13, displays a checking wheel for the 9-function, whereas a checking wheel for the 11-function is placed behind a window 17. A row of 9 keys 18 is associated with the first-mentioned checking wheel, and a row of 11 keys 19 with the second checking wheel.

In operation, when a number is selected by means of the key board 15, the 9-function of this number must be selected by means of the key group 18, and the 11-function by means of the key group 19. Thus, these functions are treated in the same manner as the number itself, and if the selection and calculation are correctly performed, the 9-function and the 11-function of any number visible through slot 13 will correspond with the figures displayed by windows 16 and 17, respectively.

The apparatus further comprises a row of nine signal lamps 20 and a row of eleven signal lamps 21. The 9-function and the 11-function of each number displayed by the slot 13 are automatically computed, but not visibly shown. However, if these functions do not correspond with the figures shown at the windows 16 and 17, a lamp indicating the difference is lighted in row 20 and/or in row 21. As long as the lamps "0" are lighted in both rows, there is no difference, i. e. no error occurs.

Fig. 2 shows a disc 25, bearing a plurality of brushes 26 divided over radii indicated at 0, I, II . . . IX. Moreover, a brush 27 is more inwardly arranged on the 0-radius, and a brush 28 is arranged outside the circle of the brushes 26. All these brushes are stationary.

Brush 27 is connected with the current supply 29, which is controlled by a switch 30. The ten brushes 26 and the brush 28 are each connected with a signal lamp 21 (cf. Fig. 1), these lamps being grounded at 31, or connected with the other terminal of the voltage source.

Brushes 26, 27 and 28 cooperate with contact members on the left-hand side of the first figure wheel 14¹ as shown in Fig. 3. Brushes 26 cooperate with contact segments 32 arranged in a circle, brush 28 cooperates with a contact ring 33, and brush 27 either with contact ring 34, or with a contact segment 35 placed in an interruption of ring 34.

Contact members are also provided on the right-hand side of figure wheel 14¹ as shown in Fig. 3 at the right. These contact members are contact rings formed in such manner that each ring extends over part of its circumference in one circle, and over the remainder of its circumference in another circle, so that two different contact rings lie in each complete circle. Nine of these contact rings are provided and shown at 40 in the drawing. They are connected by means of electric conductors 41 with the contact segments 32 on the left-hand side of the

figure wheel 14¹; however, the contact segment 32 lying on the 0-radius is connected with the innermost contact ring 43 on the right-hand side of the figure wheel 14¹, this contact ring 43 being closed, i. e. extending through 360°.

The innermost contact ring 34 on the left-hand side is connected with a contact segment 46 lying on the 0-radius outside the contact rings 40 on the right-hand side of the figure wheel. The contact ring 33 at the left is connected with a large contact segment 44 at the right, arranged in the interruption of contact rings 40, and the small inner segment 35 at the left is connected with an outside segment 45 at the right, placed on the 9-radius opposite to the large segment 44.

A stationary disc 50, shown in Fig. 4, is facing the right-hand side of the figure wheel 14¹ shown in Fig. 3. The left-hand side of this disc, cooperating with the right-hand side of figure wheel 14¹, is provided with a plurality of brushes divided over ten radii, indicated at 0, I, II . . . IX. The brushes 51 are arranged in a spiral and cooperate with the contact rings 40 and with the large contact segment 44, whereas the brushes 52, arranged in a large circle, cooperate, for instance, with the contact segment 45 in Fig. 3. Moreover, a brush 53 cooperates with the innermost contact ring 43 in Fig. 3.

The other side of disc 50 is likewise provided with stationary contact brushes. The brush 53 on the left-hand side is electrically connected with a brush 55 arranged on the 0-radius on the right-hand side. At the same distance from the centre, but divided over ten radii (0, I, II . . . IX), brushes 56 are provided, which are connected with the spirally arranged brushes 51 on the left-hand side in such manner that brushes on corresponding radii are interconnected.

The nine brushes 52 on the left-hand side, arranged on the outermost circle, are connected with nine brushes 57 on the right-hand side, which are arranged in a spiral, brushes lying on corresponding radii being interconnected.

At the right of the disc 50 shown in Fig. 4, a normal figure wheel 60 as shown in Fig. 5 is arranged. At the right of this figure wheel, a disc as shown in Fig. 4 follows; this disc is again followed by a figure wheel, and so on, according to the number of figure wheels pertaining to the counting mechanism.

Both sides of the figure wheel 60 are again provided with contact rings of the same kind as shown on the right-hand side of Fig. 3. However, the rings on the left-hand side are provided with interruptions at different places, and the rings on the right-hand side with interruptions at the same place. The rings 61 on the left-hand side are electrically connected with the contact segments 62, which are circumferentially spaced with respect to each other on the largest circle of the right-hand side. The left-hand side also comprises a plurality of contact segments 63, which are circumferentially spaced with respect to each other, and which are connected with the contact rings 64 on the right-hand side. The outermost uninterrupted contact ring 65 on the left-hand side is connected with the large contact segment 66 on the right-hand side of figure wheel 60.

At the right of the first figure wheel from the right (14⁷ in Fig. 1), a disc 70 is provided, of which the left-hand and right-hand sides are shown in Fig. 6. The left-hand side is provided with a plurality of contact brushes cooperating with the right-hand side of figure wheel 60.

(Fig. 5), to wit a brush 71 arranged on the 0-radius at a small distance from the centre, and ten brushes 72, arranged in a spiral. These brushes are connected with contact brushes on a further disc 90, shown in Fig. 8, and arranged between the checking wheels 16 and 17 shown in Fig. 1. Thus, the conductors 73 in Fig. 6 are continued by the conductors 73 in Fig. 8.

The disc 70 further comprises nine contact brushes 74, arranged in a large circle and divided over nine of the ten radii. These contact brushes are connected through conductors 75 with nine contact brushes 76 on the right-hand side of disc 70, which are divided over nine concentric circles.

At the right-hand side of disc 70 (Fig. 6), the 9-wheel 16 shown in Fig. 1 is arranged. This wheel is only provided with nine concentric contact rings 81 on the left-hand side, and with nine contact segments 82, electrically connected with the said concentric rings 81, and arranged in a large circle, on the right-hand side.

At the right of the 9-wheel 16, as shown in Fig. 7, the above-mentioned disc 90 is arranged. The left-hand side of this disc is provided with nine contact brushes, each connected with one of the nine signal lamps 20, the remaining terminals of these lamps being grounded at 91, or connected with one of the terminals of the electric mains. The right-hand side of disc 90 carries eleven contact brushes divided along a large circle, and connected through conductors 73 with the contact brushes 71, 72 of disc 70, as shown in Fig. 6.

The 11-wheel 17 shown in Fig. 9 is facing the right-hand side of the contact disc 90 shown in Fig. 8. On its left-hand side, the 11-wheel carries only one contact segment 91, arranged on the 0-radius and engaging the brushes of disc 90 as shown in Fig. 8, whereas the right-hand side of the 11-wheel carries only one contact ring 92, electrically connected with said segment 91.

Opposite to contact ring 92, a single contact brush 93 is arranged on an end wall 94 of casing 12, as shown in Fig. 10. Contact brush 93 is connected with the mains through a switch 95.

In Figs. 2-10, all figure wheels display the figure zero, as shown in Fig. 1. Hence, the 9-function and the 11-function of the figure wheels are both equal to zero, which corresponds with the zero positions of the checking wheels 16 and 17. The circuit is as follows:

In Fig. 2, the current flows from the current source through conductor 29 and switch 30 to contact brush 27, and thence to the ring segment 34 on the left-hand side of the first figure wheel from the left, as shown in Fig. 3. From this segment, the current flows to the outermost segment 46 on the 0-radius on the other side of figure wheel 14¹, so as to be taken up by brush 52 on the 0-radius of the stationary disc 50 shown in Fig. 4. From this brush, the current flows to the innermost brush 57 on the 0-radius of the right-hand side of disc 50, and thence to the innermost ring 61 on the left-hand side of the first figure wheel 60 as shown in Fig. 5. From this ring, the current flows to segment 62 on the 0-radius of the right-hand side of the same figure wheel.

After that, the circuit as described from brush 52 on the 0-radius of disc 50 (Fig. 4) to the next figure wheel is repeated, until all figure wheels have been passed, and eventually, disc 70 as shown in Fig. 6, at the right of the last figure wheel is reached. On this disc, the current is

taken up by brush 74 on the 0-radius, so as to be conducted to the innermost brush 76 on the 0-radius of the right-hand side of disc 70. This brush transfers the current to innermost contact ring 81 of the 9-wheel 16 as shown in Fig. 7. From this ring, the current flows to contact segment 82 on the 0-radius of the right-hand side of the 9-wheel 16, and thence through the 0-brush of disc 90 in Fig. 8 to the 0-lamp 20, which indicates that no difference of the 9-functions is present.

In opposite sense, a current flows through switch 95 in Fig. 10 to brush 93, and thence to contact ring 92 on the right-hand side of the 11-wheel shown in Fig. 9. From this ring, the current flows to contact segment 91 on the right-hand side of the 11-wheel, so as to be taken up by the 0-brush on the right-hand side of disc 90, as shown in Fig. 8. Thence, the current flows through the first conductor 73 from the right to the first conductor 13 from the right in Fig. 6, so as to reach brush 71, which transfers the current to the innermost uninterrupted contact ring on the right-hand side of the figure wheel shown in Fig. 5. From this ring, the current flows to segment 63 on the 0-radius on the left-hand side of the figure wheel and now the same circuit is repeated for all figure wheels, as the current flows from said segment 63 on the 0-radius to brush 55 as shown in Fig. 4, and thence to brush 53 on the left-hand side of disc 50 as shown in the same figure, so that it reaches the innermost contact ring on the right-hand side of the next figure wheel. This procedure is repeated until the current reaches the innermost contact ring 43 of the first figure wheel from the left as shown in Fig. 3. From this ring, the current flows to contact segment 32 on the 0-radius of the left-hand side of the first figure wheel from the left 14¹, so as to be taken up by contact brush 26 on the 0-radius of disc 25 as shown in Fig. 2. Thence, the current flows to the 0-lamp 21, indicating that no difference of the 11-functions is present.

Now, a case will be discussed, wherein a difference of the 9-functions and the 11-functions exists. For the sake of simplicity, it will be assumed that the counting mechanism comprises only two wheels, to wit the first figure wheel from the left 14¹ as shown in Fig. 3, and one further figure wheel 60 as shown in Fig. 5. Suppose that the left figure wheel displays the figure 1 and the other figure wheel the figure 2, so that the 9-function is equal to 3.

The circuit for the 9-function will now be as follows:

From switch 30 in Fig. 2, the current flows to the innermost contact brush, and thence through contact ring 34 in Fig. 3 to segment 46 in Fig. 3, which now faces the contact brush 52 on the I-radius as shown in Fig. 4. From this brush the current flows to contact brush 57 on the I-radius of the right-hand side of disc 50 as shown in Fig. 4, and thence to the second contact ring 61 from the inside on the left-hand side of figure wheel 60 as shown in Fig. 5. This contact ring is connected with contact segment 62 on the 9-radius of the right-hand side of figure wheels 60 as shown in Fig. 5, which now faces brush 74 on the III-radius in Fig. 6. Thence, the current flows to brush 76 on the IV-radius in Fig. 6, so as to reach the third annular segment 81 from the outside on the left-hand side of the 9-wheel 16 as shown in Fig. 7. From this segment, the current flows to segment 82 on the 3-radius

10

of the right-hand side of the 9-wheel, if the latter still occupies its zero position. Thence, the current flows through brush III in Fig. 8 to the 3-lamp, which is lighted. This obtains for the case that the 9-wheel as shown in Fig. 7 has been left in the zero position. The 9-wheel then indicates a 9-function zero, whereas the figure wheels produce a 9-function 3. The difference between the 9-functions is 3, which is shown by the 3-lamp 20.

If the 9-wheel 16 would also have been rotated over three steps so as to indicate a 9-function 3, brush 82 on the 3-radius in Fig. 7 would have reached the position of the 0-radius, so that the 0-lamp 20 would have been lighted, indicating that no difference occurs between the 9-function produced by the figure wheels 14 and the 9-function displayed by the checking wheel 16. In other words, as long as the 0-lamp is lighted, no errors have been made.

For the 11-function, it is to be noted that the figure values of the odd figure wheels must be added together, and decreased by the sum of the figures appearing in the even positions. Of course, the contacts on the figure wheels have been arranged so as to comply with this requirement. In fact, the connections between the input and output brushes of consecutive figure wheels are complementary, so that the right one is always subtracted from the left one. Suppose that the standard figure wheel as shown in Fig. 5 and the first figure wheel from the left as shown in Fig. 3 both occupy an odd position. Thus, the values displayed by these figure wheels must be added together. For the sake of simplicity, it will further be assumed that the intermediate figure wheels for the even positions occupy their zero positions. This assumption is made because the figure wheels have been drawn in their zero positions, and not because the circuit would be simpler.

It will again be assumed that the left figure wheel displays the figure 1 and the other figure wheel the figure 2, so that, for instance, the number 102 is displayed by the counting mechanism. The 11-function of this number is equal to 3. The circuit for the 11-function is as follows:

First, it will be assumed that the 11-wheel as shown in Fig. 9 occupies its zero position. The difference between the 11-functions is equal to 3 in this case, so that the 3-lamp in Fig. 2 will be lighted.

The current flows from switch 95 in Fig. 10 to contact brush 93, and thence through contact ring 92 in Fig. 9 to contact segment 91 in the same figure. After that, the current is taken up by the contact brush on the 0-radius in the top half of Fig. 8, so that it flows through conductor 8 in Fig. 6 and reaches contact brush 71 on the innermost circle on the left-hand side in Fig. 6. Thence, the current passes on to the innermost contact ring at the right in Fig. 5, so as to reach the contact segment on the 0-radius on the second circle from the outside at the left in Fig. 5. This contact segment has been rotated over two steps, so that it occupies the position of the 8-radius, and the current is taken up by the contact brush shown at the top in Fig. 4 on the 2-radius on the second circle from the outside. Thence, the current flows to the contact brush shown at the bottom in Fig. 4 on the 2-radius on the third circle from the outside. Through the next figure wheel, which occupies its zero position, the current reaches brush 51 shown at the

bottom in Fig. 4 on the IX-radius on the third circle from the inside, and passes on to the third contact ring from the inside at the right in Fig. 3, so as to reach the contact segment 32 on the 8-radius at the left in Fig. 3. This segment has been displaced over one step, so that the current is taken up by the contact brush on the III-radius in Fig. 2, and flows through the 3-lamp as required.

However, if the 11-wheel as shown in Fig. 9 would have been rotated over three steps, the circuit would have been as follows:

From contact brush 93 in Fig. 10, the current again reaches segment 91 in Fig. 9 through contact ring 92. However, segment 91 occupies the position of the 8-radius, so that the current is taken up by the contact brush on the 8-radius at the top in Fig. 8, and flows through conductor 8 to contact brush 12 on the 3-radius in Fig. 6 on the fourth circle from the outside. This brush transfers the current to the segment 66 at the right in Fig. 5 in the position of the 1-radius (the figure wheel has been rotated over two positions) and thence the current flows to contact ring 65 on the 2-radius at the left in Fig. 5, which occupies the position of the 0-radius. Thence, the current flows to contact brush 55 on the 0-radius at the top in Fig. 4 on the innermost circle, so as to reach contact brush 51 on the 0-radius on the second circle from the inside at the bottom of Fig. 4. Now, the current flows to the next figure wheel, which occupies its zero position, so that it reaches the second contact ring from the inside. Thence, the current flows through a contact segment 63 on the 9-radius and brush 56 on the 1-radius at the top in Fig. 4 to the contact brush 51 on the 1-radius at the bottom in Fig. 4, and thence to the contact segment on the second circle from the outside. After that, the current flows to the second contact ring from the outside at the right in Fig. 3, which occupies the position of the 0-radius (the figure wheel 141 has been rotated over one position), and thence to segment 32 on the 1-radius at the left in Fig. 3, which occupies the position of the 0-radius. Thus, the current is taken up by the brush on the 0-radius in Fig. 2, so that the 0-lamp 20 is lighted. As long as the 0-lamp is lighted, no errors have been made.

In the appended claims, the term "S-function of a number" designates the remainder obtained on division of said number by a key number S.

I claim:

1. A counting mechanism, comprising a plurality of figure wheels each having n different positions, means for displacing the said figure wheels each over a number of steps corresponding with one of the digits of a number to be inserted in said counting mechanism, and an electric computing device receiving the setting of the said figure wheels and computing therefrom a check symbol indicating the remainder obtained on division by a key number S different from n of the number registered in the said figure wheels, wherein the said computing device comprises a plurality of sets of n electric contacts each fixedly coupled with one of the said figure wheels so as to be rotated upon rotation of the associated figure wheel, a plurality of sets of S fixed contacts each cooperating with one of the said first-mentioned sets of contacts, and connections between the contacts of the said first-mentioned and the last-mentioned sets, whereby an electric circuit corresponding with the check symbol of the num-

ber registered in the said figure wheels is formed through the contacts of the said sets.

2. A counting mechanism as claimed in claim 1, further comprising an S-partite checking wheel, and means for displacing said checking wheel over a number of steps corresponding with the value of a check symbol accompanying a number to be inserted in said counting mechanism, wherein the said computing device further comprises a set of S electric contacts fixedly coupled with said checking wheel so as to be rotated upon rotation of said checking wheel, a set of S fixed contacts cooperating with the contacts of the said first-mentioned set, and means connected with the said fixed contacts for signalizing any discrepancy between the check symbol of the number registered in the said figure wheels and the setting of said checking wheel.

3. A counting mechanism comprising a plurality of figure wheels each having n different positions, means for displacing the said figure wheels each over a number of steps corresponding with one of the digits of a number to be inserted in said counting mechanism, and an electric computing device receiving the setting of the said figure wheels and computing therefrom a check symbol indicating the remainder obtained on division by a key number S different from n of the number registered in the said figure wheels, wherein the said computing device comprises a plurality of rotatory sets of n radially spaced electric contacts each fixedly coupled with one of the said figure wheels so as to be rotated upon rotation of the associated figure wheel, a plurality of rotatory sets of n circumferentially spaced electric contacts each fixedly coupled with one of the said figure wheels so as to be rotated upon rotation of the associated figure wheel, connections between the radially spaced contacts of each set and the circumferentially spaced contacts of the related set, a plurality of sets of S radially spaced fixed contacts each cooperating with one of the said first-mentioned sets of radially spaced contacts, a plurality of sets of S circumferentially spaced fixed contacts each cooperating with one of the said first-mentioned sets of circumferentially spaced contacts, and connections between the radially spaced fixed contacts associated with each figure wheel and the circumferentially spaced fixed contacts associated with the next figure wheel, whereby an electric circuit corresponding with the check symbol of the number registered in the said figure wheels is formed through the contacts of the said sets.

4. A counting mechanism as claimed in claim 3, further comprising an S-partite checking wheel, and means for displacing the said checking wheel over a number of steps corresponding with the value of a check symbol accompanying a number to be inserted in the said counting mechanism, wherein the said computing device further comprises a rotatory set of S radially spaced electric contacts fixedly coupled with said checking wheel so as to be rotated upon rotation of said checking wheel, a rotatory set of S circumferentially spaced electric contacts fixedly coupled with said checking wheel so as to be rotated upon rotation of said checking wheel, connections between the said radially spaced and the said circumferentially spaced contacts, a set of S radially spaced fixed contacts cooperating with said first-mentioned set of radially spaced contacts, a set of S circumferentially spaced fixed contacts cooperating with said first-mentioned set of circumferentially spaced contacts, a set of S circumferentially spaced fixed contacts cooperating with said first-men-

tioned set of circumferentially spaced contacts, connections between the contacts of one of the said sets of fixed contacts and the contacts of one of the sets of fixed contacts associated with the adjoining figure wheel, indicating means for signaling any discrepancy between the setting of said checking wheel and the check symbol of the number registered in the said figure wheels, and connections between the contacts of the other one of the said sets of fixed contacts and the said indicating means.

5. A counting mechanism as claimed in claim 4, wherein the said indicating means comprise a set of glow lamps each connected with one of the contacts of one of the sets of fixed contacts associated with said checking wheel.

6. A counting machine, comprising a plurality of figure wheels each having n different portions, means for displacing the said figure wheels each over a number of steps corresponding with one of the digits of a number to be inserted in said counting mechanism, and an electric computing device receiving the setting of the said figure wheels and computing therefrom a check symbol indicating the remainder obtained on division by a key number S different from n of the number registered in the said figure wheels, wherein the said computing device comprises a plurality of sets of n radially spaced contacts each arranged on one of the said figure wheels, a plurality of sets of n circumferentially spaced contacts each arranged on one of the said figure wheels, connections between the radially spaced contacts and the circumferentially spaced contacts on each of the said figure wheels, a plurality of sets of S radially spaced fixed contacts each cooperating with one of the said first-mentioned sets of radially spaced contacts, a plurality of sets of S circumferentially spaced fixed contacts each cooperating with one of the said first-mentioned sets of circumferentially spaced contacts, and connections between the radially spaced fixed contacts associated with each figure wheel and the circumferentially spaced contacts associated with the next figure wheel, whereby an electric circuit corresponding with the check symbol of the number of registered in the said figure wheels is formed through the contacts of the said sets.

7. A counting mechanism as claimed in claim 6, further comprising an S -partite checking wheel, means for displacing said checking wheel over a number of steps corresponding with the value of a check symbol accompanying a number to be inserted in said counting mechanism, wherein the said computing device further comprises a set of S radially spaced electric contacts arranged on said checking wheel, a set of S circumferentially spaced electric contacts arranged on said checking wheel, connections between the said radially spaced and the said circumferentially spaced contacts, a set of S radially spaced fixed contacts cooperating with said first-mentioned set of radially spaced contacts, a set of S circumferentially spaced fixed contacts cooperating with said first mentioned set of circumferentially spaced contacts, connections between the fixed contacts of one of the said sets and the fixed contacts of one of the sets associated with the adjoining figure wheel, indicating means for signaling any discrepancy between the setting of said checking wheel and the check symbol of the number registered in the said figure wheels, and connections between the fixed contacts of the

other one of the said sets and the said indicating means.

8. A counting mechanism as claimed in claim 7, wherein the said indicating means comprise a set of glow lamps each connected with one of the contacts of one of the sets of fixed contacts associated with said checking wheel.

9. A counting mechanism, comprising a plurality of figure wheels each having n different positions, means for displacing the said figure wheels each over a number of steps corresponding with one of the digits of a number to be inserted in said counting machine, and an electric computing device receiving the setting of the said figure wheels and computing therefrom a check symbol indicating the remainder obtained on division by a key member S different from n of the number registered in the said figure wheels, wherein the said computing device comprises a plurality of rotatory contact members, each coupled with one of the said figure wheels, each adapted to be set in n different positions according to the position of the associated figure wheel, and each comprising n radially spaced annular contacts each extending through part of a circle, n circumferentially spaced contacts, and means electrically connecting the said radially spaced contacts each with one of the said circumferentially spaced contacts, a plurality of sets of S radially spaced stationary contact brushes each associated with one of the said contact members and cooperating with the said radially spaced contacts thereof, a plurality of sets of S circumferentially spaced stationary contact brushes each associated with one of the said contact members and cooperating with the said circumferentially spaced contacts thereof, and means electrically connecting the said radially spaced contact brushes of each set with one of the said circumferentially spaced contact brushes of an adjacent set, whereby an electric circuit corresponding with the check symbol of the number registered in the said figure wheels is formed through the said contact members and the said stationary contact brushes.

10. A counting mechanism as claimed in claim 9, further comprising a checking wheel having S different positions, and means for displacing said checking wheel over a number of positions corresponding with the value of a check symbol accompanying a number to be inserted in said counting mechanism, wherein the said computing device further comprises a rotatory contact member coupled with said checking wheel, adapted to be set in S different positions according to the position of said checking wheel, and comprising S radially spaced annular contacts, S circumferentially spaced contacts, and means electrically connecting the said radially spaced contacts each with one of the said circumferentially spaced contacts, a set of S radially spaced stationary contact brushes cooperating with the said radially spaced contacts, a set of S circumferentially spaced stationary contact brushes cooperating with the said circumferentially spaced contacts, means electrically connecting the contact brushes of one of the said sets each with one of the contact brushes of one of the sets associated with the adjoining figure wheel, indicating means for signaling any disagreement between the setting of said checking wheel and the check symbol of the number registered in the said figure wheels, and means connecting the contact brushes of the other set with the said indicating means.

13

11. A counting mechanism as claimed in claim 10, wherein the said indicating means comprise a set of glow lamps each connected with one of the contact brushes of one of the sets associated with said checking wheel, and indicating the difference between the setting of said checking wheel and the check symbol of the number registered in the said figure wheels.

12. A counting mechanism as claimed in claim 9, wherein the said contact members are each 10 formed as a plurality of contacts arranged on

14

the side faces of one of the said figure wheels, the radially spaced contacts being arranged on one of the said side faces and the circumferentially spaced contacts being arranged on the other side face.
